FLASHLIGHT OR SIMILAR ARTICLE

Sidney Schwartz, New York, N. Y., assignor to Bantam-Lite, Inc., New York, N. Y., a corporation of New York

Application July 13, 1950, Serial No. 11,106

Term of patent 14 years

(Cl. D48—24)

To all whom it may concern:

Be it known that Sidney Schwartz, a citizen of the United States and resident of New York city, New York, has invented a new, original, and ornamental Design for a Flashlight or Similar Article, of which the following is a specification, reference being had to the accompanying drawing, forming part thereof, in which

The single drawing figure is a front perspective view of a flashlight showing my new design.

The right end opposite the one shown is substantially the same as that illustrated, and the back is a flat plain surface.

I claim:

The ornamental design for a flashlight or similar article, as shown and described.

SIDNEY SCHWARTZ.
